UNITED STATES PATENT OFFICE.

MARTIN DRESCHER, OF NORWOOD, OHIO.

PLANT-MARKING STAKE.

Application filed September 14, 1927. Serial No. 219,543.

This invention relates to markers for identifying plants, etc., and is particularly directed to a post or stake type in which a label or tag is provided separable from the post.

5 It is an object of this invention to provide a post or stake adapted to display and mount tags in and from which the tags are easily and quickly inserted or removed.

Another object is to provide a stake structure for mounting and displaying marking tags in which the tag is positively locked and set into the stake upper end so as to be securely held against accidental displacement.

Still another object is to provide a tag, 15 easily insertable in this type of marking stake, which is weatherproof and at the same time bendable without injury to the tag or printing thereon.

Another object is to provide a mounting 20 for a tag in this type of stake, which displays both sides of the tag for increased writing space on the tag.

Further objects and advantages will be more fully set forth in the description of the 25 accompanying drawings forming a part of this specification, in which:

Figure 1 is a front view of the improved marking stake.

Figure 2 is a sectional view taken on line 30 2—2, Figure 1, showing the tag receiving portion of the stake and the tag in section.

Figure 3 is a face view of one of the tags or labels.

Figure 4 is a side elevation of the tag shown 35 in Figure 3.

Referring to the drawings, the stake comprises a straight post or standard 1 formed of straight bar metal and a tag receiving plate 2 riveted to the upper end of the standard 1. 40 The lower end of the standard 1 is pointed as at 3 so as to be easily driven into the ground. The tag receiving plate is slightly wider than the standard and has a pair of cross slots 4 and 5 cut therein. These slots are of the

45 proper dimension to receive a tag 6. The tag 6 formed of thin sheet zinc for flexibility and durability, comprises a straight face 7 for the written matter and an offset shank portion 8,

the offset portion 8 serving for attaching purposes hereinafter described. 50

The offset shank portion 8 is inserted through the lower slot 5, and the shoulder 9 formed by the offset engages the side walls of the slot, preventing lengthwise movement of the tag. The upper end of the tag receiving 55 plate 2 is offset as at 10 at the point of the slot 4 so that the straight upper portion of the tag is freely passed straight through the slot 4 without being bent at this point.

In order to insert the upper end of the tag 60 in the upper slot, the user bows the body of the tag from the point of offset to the upper end of the tag and inserts the upper end of the tag in the upper slot. Flattening out of the tag at this time pushes the upper tag end 65 through the slot, and the body flattens out on the tag receiving portion. That area of the tag receiving portion directly behind the tag body is completely cut away as at 11 up to within a slight distance of the respective slots 70 4 and 5. This cut away portion is of the same width as the slots. By the provision of this large opening through the tag receiving portion, the user is able to push against the back of the tag for removing the tag by bowing the 75 tag in the same manner in which it is bowed for insertion in the stake. The opening also permits the rear side of the tag to be visible for displaying any additional writing which may be put thereon due to lack of space on the 80 front side of the tag.

Having described my invention, I claim:

A marker for the purpose described, comprising, a standard, and a tag, the upper end of said standard having a pair of cross slots 85 formed therein, said tag bendable for insertion of its ends in said slots, and having an offset intermediate its ends adapted to engage through one of said slots for preventing accidental longitudinal displacement of the tag, 90 the standard offset at the point of the other slot for flat tag insertion through the slot.

In witness whereof, I hereunto subscribe my name.

MARTIN DRESCHER.
